UNITED STATES PATENT OFFICE.

JAMES E. BOYLE, OF BROOKLYN, NEW YORK.

WATER-CLOSET.

SPECIFICATION forming part of Letters Patent No. 255,485, dated March 28, 1882.

Application filed August 5, 1881. (No model.)

To all whom it may concern:

Be it known that I, JAMES E. BOYLE, a citizen of the United States, residing in Brooklyn, in the county of Kings and State of New York, 5 have invented certain Improvements in Water-Closets, of which the following is a specification.

My invention relates to what are known as "water-surface" closets, or those in which the 10 soil is deposited into a receptacle containing water.

Figure 1 of the accompanying drawings is a vertical mid-section of my improved closet and the apparatus pertaining thereto, viewed from 15 the front; and Fig. 2 is a side elevation of the closet alone.

A is the bowl. a is the exit-aperture thereof, and B is the soil pipe or passage leading therefrom. This pipe or passage curves upward 20 from the orifice a, forming thereby a trap, C, of which the bowl A forms one leg, and which consequently acts to retain the water in the bowl, and also prevents any escape of sewer-gas from the soil-pipe into the bowl. From 25 the trap C the pipe or passage B extends downward, and is there formed into another trap, D, from which the soil-pipe b leads to the sewer in the usual manner. A pipe, f', leads from just below the trap D to the open air, at the 30 roof or elsewhere, to give free vent to gases rising through the pipe b in the usual manner. Between the traps C and D is a confined air-space, d, from which leads a suction-pipe or air-pipe, e.

Above the bowl, and near the ceiling of the 35 room, is placed a tank, E, which in the main is of the ordinary construction. This tank is fed from the service-pipe of the building through a self-closing float-valve or ball-cock, whereby 40 a nearly uniform level is at all times secured. This cock is not shown in the drawings, being well known. A chamber, F, which serves both as a flushing and suction chamber, is formed in the tank E by means of a bulk-head or partition, as shown, or it may be a separate vessel 45 from the tank. The suction-pipe e enters this chamber and opens at its top above the highest water-level in the tank. From the chamber F a pipe, f, leads to the roof or into 50 a chimney, or otherwise communicates with the open air in any known way. The pipe f' is

preferably a branch of this air-pipe. A check-valve, g, is interposed between the pipe f and the chamber F. This valve may be of the usual construction, so as to freely permit the 55 ascent of gases, but prevent their descent into the chamber; but I prefer to employ the special construction shown, which I will herein-after describe.

From the chamber F a flushing-pipe, l, leads 60 to the flushing-rim k of the bowl A. Two valves are provided, an inlet-valve, as at h, to control the admission of water from the tank E to the chamber F, and an outlet-valve, as at j, to control the discharge from the chamber into the 65 pipe l, both being operated through a weighted lever, as p, from below—say from a pull or by other means—so that when either is open the other must be closed.

So far as already described there is no substantial novelty in this closet, nearly the same construction being embodied in English Patent No. 1,207 of 1874. My apparatus differs from that in the following-described respects: The check-valve g opens directly into the chamber 75 F, (instead of into a bend in the pipe e, as in the English patent,) and from it a tube, g', extends down into the lower portion of the chamber, its lower end opening thereinto and its upper end opening above the valve. This tube, if 80 fixed to the valve, should be light, that it may not interfere with the lifting of the valve; but it is only essential that its upper end have ultimate communication with the atmosphere.

The valves h and j, I have shown as working 85 each against an upturned seat, the valve j closing over an opening, i, leading to a service-box, G, which I have shown as interposed between the chamber F and the pipe l. An air-pipe, m, extends upward from the service-box G to 90 above the highest water-level in the tank E. Another open-topped air-pipe, n, passes down through the chamber F, and its lower end projects below and incloses the upturned valve-seat i and terminates slightly above the bottom of the chamber. The normal water-level in the chamber is determined by the height of the valve-seat i, and as the pipe n extends below that level its bottom edge is immersed in the water, thus sealing it and preventing any 95 escape of air from the chamber F into the room. The valves j and h are the ordinary waste-pre-

venting tank-valves used with hopper-closets from time immemorial. Their stems extend upward and bear nuts or adjustable collars, which in operation are engaged by opposite 5 arms of a weighted lever, *p*. When this lever is at mid-stroke or in a horizontal position both valves are seated; but when it is tilted in either direction one of the valves is raised or unseated. Its shaft or fulcrum-arm bears an arm, *p'*, 10 (shown in dotted lines in Fig. 1,) which projects on the opposite side of the fulcrum from the weight, and a wire or chain, *q*, (also shown in dotted lines,) extends downward, and is connected to the hinged seat of the closet (not 15 shown) in the well-known manner. The weight on lever *p* normally keeps the valve *j* unseated and the water-closet seat lifted slightly.

The operation of my closet is as follows: 20 The drawings show the normal condition and position of the parts, or that assumed when not in use. The chamber *F* is filled with air above the level of the valve-seat *i*. The service-box *G* and flushing-pipe *l* are empty of water. When the water closet seat is depressed 25 by the weight of the user the lever *p* is pulled down by the wire *q*, thereby dropping the valve *j* onto its seat and immediately afterward lifting the valve *h*. While the parts are in these positions the water from the tank *E* 30 flows through the seat of the valve *h* into the chamber *F*, in which it rises to the same level as in the tank, while the air in the chamber passes the valve *g* and escapes through the pipe *f*. While the water-level in the chamber 35 is below the bottom of the air-tube *g'* the air escapes through that tube; but after the water rises above and seals its end the escaping air must lift the valve *g*. When the user rises from the seat the working parts all return to 40 the position shown, whereupon the water in the chamber *F* rushes out through the opening *i* into the service-box *G*, whose capacity equals or exceeds that of the bowl *A* from the dotted line *x* up to the normal water-level, (see Fig. 1,) 45 quickly fills this box, and proceeds to descend through the pipe *l*. The rapid fall of water from the chamber *F* creates a partial vacuum therein, which causes a strong suction in the pipe *e*, thereby drawing the water from the 50 trap *C*, causing it to fall over into the trap *D*, and lowering the water-level in the bowl to the line *x*, whereupon the vacuum is broken by the entrance of air from the bowl 55 into the air-space *d*. This indraft of air from the bowl insures the drawing from the room of all, or nearly all, the foul odors resulting from the use of the closet. This operation is completed and may be repeated once or often- 60 er (according to the proportioning of these sever- al parts) before the flushing-water descending through the pipe *l* reaches the bowl, whereupon the latter is refilled, and before the water-level in the chamber *F* descends to the bottom of the tube *g'*, or near enough thereto to pre- 65 vent the entrance of air through said tube to break the vacuum in the chamber. Prior to

the vacuum being so broken the water is somewhat retarded in its flow from the chamber *F* by the suction behind it; but after unsealing the bottom of the tube *g'* the admission of air through that tube sets free the remaining water, causing a full downward flow through the pipe *l*, thereby filling the bowl above its normal water-level and causing a forcible current outward through the trap *C*. 70 As the flushing-water is several times the volume of the water in the bowl and trap *C*, that water, with the excrement and paper held in it, is all forced beyond the trap *C*, and its place is taken by fresh clean water. 75

The service-box *G* and its air-pipe *m* serve much the same purpose as the air-tube *g'* in retarding the flow of water at first and afterward freeing and accelerating it, and may be used in connection with the air-tube, as shown, 80 or as a partial substitute therefor in case of its omission.

The most important and essential feature of novelty in my closet is the means I have provided for securing a thorough and abundant 85 "after-wash," the flushing-water being freed from the retarding influence of the partial vacuum above it as soon as that vacuum has done its work of siphoning the bowl, instead of leaving the vacuum unbroken, as heretofore, 90 so that the contents of the bowl will be siphoned out nearly as fast as they are supplied—a defect which my invention entirely remedies.

By my arrangement of the valves *h*, *j*, in connection with the seat, the chamber *F* is normally empty of water, so that any sewer-gas which may possibly pass the trap *D* will have free escape through the pipe *e*, valve *g*, and pipe *f*, and in case of any suction in the sewer-pipe air may freely enter through the 100 pipes *g'* or *n* and pass down through the pipe *e*; and there is also no possibility of excrement being left in the bowl through forgetfulness, as in the use of closets operated by a pull-handle. In case of suddenly dashing a pail 105 of water or slops into the bowl *A*, any extra pressure in the space *d* thereby caused would be relieved by an escape of air through the tube *g'* or valve *g*.

I form the bowl *A* and traps *C* and *D* all in one piece of earthenware; and in order to bring both traps above the floor and save cutting into the latter, and to avoid raising the seat above its proper height, I have devised the relative arrangement of traps shown. The 110 trap *C*, of which the bowl *A* forms one leg, extends to one side of the bowl, and its other leg extends upward close alongside the bowl. From this leg the receiving-leg of the trap *D* 115 extends down to the floor, and its other leg extends thence laterally and upwardly close under the trap *C* and bowl *A*, and (in order to carry it to the necessary height) beyond the center of the bowl, whence the passage curves back underneath it and terminates at the floor, 120 directly under the center of the bowl by preference, so that my closet can be substituted 125

for the usual pan and other closets without altering the wood-work or moving the soil-pipe *b*. Thus it will be seen that instead of placing the belly or lowest part of the trap *C* directly over the crown or highest part of the trap *D*, as heretofore, the belly of the trap *C* is arranged to depend into the space between the two legs of the trap *D*, and the crown of the latter is arranged to one side of the belly of the former, thus rendering the closet much more compact vertically.

My invention is susceptible of considerable formal or structural modification without departing from its essential features. If an automatic closet is not desired, the lever *p* may be arranged with the weight on the opposite arm, so as to stand normally in the position opposite to that shown, and be so arranged in connection with a pull-handle as to be tilted into the position shown when the handle is lifted. The chamber *F* will then fill while the closet is not in use, and will be discharged while the pull-handle is upheld.

I claim as my invention—

- 25 1. A water-closet bowl forming one leg of a trap, a second trap below the first, an exhaust-pipe leading from the air-space between the two traps and terminating near the top of a flushing-chamber, the said chamber provided with inlet and outlet valves, and a flushing-pipe leading from the outlet-valve thereof to the bowl, all in combination, with suitable means, substantially as hereinbefore set forth, for preventing further retardation of the flow of flushing-water after the bowl has been siphoned by the partial vacuum formed by the descent of water in the flushing-chamber, thereby augmenting the after-wash and insuring the final filling of the bowl.
- 40 2. A water-closet bowl formed as one leg of a trap, a second trap below the first, an exhaust-pipe leading from the air-space between the two traps to the upper part of a flushing-chamber, the said chamber provided with inlet and outlet valves, and a flushing-pipe leading from the outlet-valve thereof to the bowl, all in combination, with suitable means, substantially as hereinbefore set forth, for automatically breaking the vacuum in said chamber when the water-level therein has descended to a predetermined point.
- 50 3. A water-closet bowl formed as one leg of a

trap, a second trap below the first, an exhaust-pipe leading from the air-space between the two traps to the upper part of a flushing-chamber, the said chamber provided with inlet and outlet valves, and a flushing-pipe leading from the outlet-valve thereof to the bowl, all in combination with an air-pipe entering said flushing-chamber and opening therein in the lower portion thereof, substantially as and for the purposes set forth.

4. A water-closet bowl formed as one leg of a trap, a second trap below the first, an exhaust-pipe leading from the air-space between the two traps to the upper part of a flushing-chamber, the said chamber provided with inlet and outlet valves, and a flushing-pipe leading from the outlet-valve thereof to the bowl, all in combination with a check-valve opening outwardly from the top of the flushing-chamber, and an air-tube extending into the latter and opening therein about midway of its height, substantially as set forth.

5. The combination of bowl *A*, traps *C* and *D*, air-space *d*, pipe *e*, chamber *F*, pipe *n*, depending into said chamber, valve-seat *i*, projecting up inside the pipe *n*, valve *j*, normally unseated, pipe *l*, leading from said seat *i* to the bowl *A*, a normally-closed inlet-valve for the chamber *F*, and means for opening said inlet-valve and closing the valve *j* upon the depression of the water-closet seat, substantially as and for the purposes set forth.

6. The combination of bowl *A*, traps *C* and *D*, air-space *d*, pipe *e*, chamber *F*, inlet and outlet valves therefor, service-box *G*, into which said outlet-valve opens, air-pipe *m*, and flushing-pipe *l*, substantially as set forth.

7. The combination of bowl *A* and traps *C* and *D*, molded in one piece, with the belly of the trap *C* arranged to depend between the two legs of the trap *D*, and the crown of the latter arranged to one side of the belly of the trap *C* and close underneath the bowl *A*, substantially as set forth.

In witness whereof I have hereunto signed my name in the presence of two subscribing witnesses.

J. E. BOYLE.
